UNITED STATES PATENT OFFICE.

WALTER E. ZANDER, OF PHILADELPHIA, PENNSYLVANIA, ASSIGNOR TO SCHLETER & ZANDER, INC., OF PHILADELPHIA, PENNSYLVANIA, A CORPORATION OF PENNSYLVANIA.

DESIGN FOR A STOCKING.

Application filed April 9, 1926. Serial No. 17,230. Term of patent 14 years.

To all whom it may concern:

Be it known that I, WALTER E. ZANDER, a citizen of the United States, residing at Philadelphia, in the county of Philadelphia and State of Pennsylvania, have invented a new, original, and ornamental Design for Stockings, of which the following is a specification, reference being had to the accompanying drawing, forming a part thereof, in which

Fig. 1 is a perspective, showing my new design, and

Fig. 2 is a perspective view of a stocking showing my new design.

The instep of my new stocking is reinforced lightly approximately to the height of the high splice above the heel and upwardly tapered reinforcements are located at spaced intervals around the ankle to form a V-line design.

I claim:

The ornamental design for a stocking, as shown and described.

In witness whereof, I have hereunto set my hand and seal at Philadelphia, April, A. D. 1926.

WALTER E. ZANDER. [L. S.]
